Letters Patent No. 71,215, dated November 19, 1867.

IMPROVEMENT IN AIR-TIGHT JARS.

The Schedule referred to in these Letters Patent and making part of the same.

TO ALL WHOM IT MAY CONCERN:

Be it known that I, GEORGE M. RAMSAY, of the city county, and State of New York, have invented a new and improved Mode of Constructing Air-Tight Jars.

The same principle, of interlocking the lid and making the jar tight, having been secured to me by Letters Patent, No. 54,015, no detailed description of this is therefore required.

Like letters refer to like parts in each figure.

Figure 1 represents a side view of the jar, including the lid and rubber ring. *d* represents the expanded base of the lid, *c* the neck, and *f* the rubber ring, resting on the brim of the jar and under the cap of the lid.

Figure 5 is same as fig. 1, except only the rubber *f* is made to rest on the shoulder of the jar outside of the neck of the jar.

Figures 2 and 4 represent plan views of the inlet of jars.

Figure 3 is a plan view of the lid of the jar.

The new feature and mode consist of, and are limited to, the contraction of the inlet of the jar at more than two portions or points, as represented by plan views, figs. 2 and 4, wherein letter A represents, in dotted circles, the smaller cross-diameters, and B the larger cross-diameters. When more than one cross-section of the inlet is contracted, as represented in figs. 2 and 4, the lid, when twisted, is prevented from gliding towards the longer diameters of the inlet, the diameter of the neck *c* of the lid being made near the same diameter of the dotted circles A in figs. 2 and 4, while the base *d* of the lid is made, as represented by *e*, in plan view, fig. 3, so as to conform to the shape of the inlet of the jar.

This mode of contracting the inlet of a jar is not the equivalent of lugs or projections; nor of a screw, either in sections or continuous, for the reason that my lid, when twisted either to the right or left, locks all the same. The principle upon which my lid locks arises from the fact that, in connection with the irregular-shaped inlet, the inner surface of the inlet is made to incline in a plane towards the centre, and the outer surface of the base of the lid is made to incline in a plane from the centre; whereas the inclinations of lugs, and projections, and screws are necessarily made to incline, either on the jar or on the lid, in a plane coincident with the circumference of the lid or jar.

I claim contracting the inlet of a jar at three or more portions of its cross-diameter, so as to hold the lid near the centre, substantially as and for the purpose herein set forth.

GEORGE M. RAMSAY.
